OTTO SEITER, OF FOREST HILLS WEST, NEW YORK, ASSIGNOR TO THE NESTLE-LEMUR COMPANY, OF NEW YORK, N. Y., A CORPORATION OF OHIO

HAIR WAVING APPARATUS

Application filed June 1, 1932. Serial No. 614,692.

This invention relates to improvements in the art of waving human hair and has particular reference to holding devices for a wound strand of hair.

Holding devices including clamps and curler rods have been heretofore devised wherein the clamp is utilized to grip a strand of hair close to the scalp and to receive the curler rod upon which the strand is wound. The clamp usually consists of a pair of pivotally connected bars adapted to be brought together to securely hold the hair strand therebetween, and is provided with means cooperating with the curler rod to tightly wind said strand thereon and maintain the latter under tension. The cooperating means customarily employed consists of a ratchet formed on one end of the curler rod and a pawl carried by the clamp which is engageable with the ratchet so as to prevent rotation of the rod in a direction which would relieve the tension on the hair strand and allow it to become loosened on said rod. With the strand of hair thus held between the bars of the clamp and wound on the rod, the latter is held against the clamp at least partly by the tension under which the strand has been placed, and cannot conveniently be removed until said tension is relieved. In the types of appliances heretofore used, the release of tension after treatment of the hair strand is accomplished by first separating the bars of the clamp after which the curler rod and hair strand may be shifted slightly in a longitudinal direction relative to the clamp in order to disengage the ratchet of the rod from the pawl of the clamp, whereupon the rod may be rotated to unwind the strand therefrom.

It has been found in practice that the separation of the bars of the clamp, preparatory to unwinding the hair strand after treatment, requires some skill in the proper handling of the appliances as it entails the necessity of the operator holding both the clamp and the curler rod in order to accomplish the shifting of the latter to disengage the elements of the pawl and ratchet mechanism.

In accordance with the present invention it is proposed to simplify the operation of releasing the hair strand from the curler rod by a suitable means the use of which will avoid the necessity of the operator first separating the bars of the clamp and holding the same while shifting the rod and strand

relative to said clamp in order to disengage the parts of said pawl and ratchet mechanism one from the other.

In accomplishing this simplification it has been found satisfactory to provide the pawl with a finger-piece by which it may be released from the ratchet mechanism, and in one preferred form of the present invention such pawl is provided with an abutment which may be desirably located to serve as a finger abutment so as to limit the movement of the pawl in releasing the ratchet.

The inventive idea involved is capable of receiving a variety of mechanical expressions, one of which, for purposes of illustration, is shown in the accompanying drawing where-

in:—

Figure 1 is a perspective view of the clamp and curler rod, illustrating a hair strand in the act of being wound upon the rod while held by the clamp.

Figure 2 is a side elevation of the clamp and rod in operative position, showing a heater applied thereto, partly broken away and shown in section.

Figure 3 is an end elevation of the assembly shown in Figure 2, also partly broken away and shown in section.

Figure 4 is a plan view of the clamp.

Figure 5 is an end elevation thereof, and

Figure 6 is a perspective view of one of the spring members employed with the heater.

The apparatus shown in the accompanying drawing consists generally of three elements, namely a clamp 10, curler rod 11 and an electric heater 12. In use, the clamp is first employed to grip a strand of hair 13 adjacent the scalp, after which said strand is wound upon the rod 11, in the manner illustrated in Figure 1. When the strand is completely wound upon the rod, the latter is unengaged with the clamp in a manner to be presently described in detail, and the strand is then wrapped in a pad or sachet (not shown) which is moistened with a hair treating solution. The heater 12 is then placed about the strand and heat applied for treatment of the strand in the customary manner.

The present clamp is shown, in its preferred form, as comprising the two cooperating clamping bars 14 and 15, the former of which is made of a suitable insulating material while the bar 15 consists of a metallic rod 16 covered by a sleeve 17 of rubber or other suitable insulation. The inner edge of

the bar 14 adjacent the bar 15 is concaved as indicated at 18 (Figure 5) so as to receive a portion of the sleeve 16 to thereby provide maximum gripping surfaces for the clamping bars which hold the hair strand therebetween.

At the ends of the bar 14 the same has suitably secured thereto the bearing members 19 and 20, the former of which is provided adjacent its base with a lug 21 to which is pivoted the adjacent end of the bar 15. The other end of said bar carries a latching device consisting of a link 22 pivoted at one end to said bar and, in turn, having pivoted to its other end a cam lever 23. When the clamping bars have been brought into cooperative relation with the strand 13 therebetween the link 22 is swung to a position parallel with and against the adjacent end of the bar 14 and the lever 23 is then extended longitudinally with the outer edge of said bar, as shown in Figure 1, to lock the clamping bars together. With the clamp in its operative position, the strand 13 is now ready to be wound upon the curler rod 11.

The body of the rod is tapered inwardly from both ends as is customary with rods of this type and adjacent one end thereof has pivoted thereto a retaining arm 24 which extends longitudinally of the rod and is adapted to have the free end of the strand interposed between the same and said rod at the beginning of the winding operation. The strand is now wound upon the rod in the manner shown in Figure 1 and as the winding operation progresses the rod approaches the clamp and finally contacts the same with the end portion 25 of the rod engaged in the recess 26 of the bearing 19 and the trunnion 27 at the opposite end of the rod engaged in the recess 28 in the bearing member 20, thereby supporting the rod on the clamp. At the outer end of the portion 25 of the rod there is formed a ratchet 29 which is disposed exteriorly of the bearing member 19 when the rod is in position and which is adapted to be engaged by a pawl member generally indicated by the numeral 30 and carried by the bar 14. This pawl and ratchet mechanism is designed to prevent rotation of the curler rod in one direction and at the same time permits of a turning of the rod in the opposite direction, by the application of a key to the squared end 31 of said rod, to tightly wind the strand 13 on the rod and thereby place said strand under the desired tension for the waving process.

The pawl member 30 specifically comprises a base portion 32 secured in the adjacent end of the bar 14 and having extending upwardly from one end thereof the curved spring arm 33 which is of sufficient length and resiliency to normally maintain the pawl or tooth 34 thereof in engagement with the teeth of the ratchet 29 and at the same time permit of the

withdrawal of said pawl from the ratchet without undue pressure having to be exerted upon said arm. The latter is extend beyond the pawl 34 to provide a fingerpiece 35 affording a means whereby the operator may easily press the arm in a direction away from the ratchet 29 and thus disengage the pawl 34 from the teeth of said ratchet. To facilitate this releasing action the bearing member 19 is provided with a second fingerpiece 36 disposed in juxtaposition to the piece 35, and being stationary, said piece 36 provides a grip by means of which the movable fingerpiece can be more readily pressed in a direction away from the ratchet 29.

In the types of clamps and curler rods usually employed, when it becomes necessary to unwind the strand of hair from the curler rod after treatment of said strand, the tension under which the latter has been placed by the winding operation causes such an interengagement of the clamp and curler rod that in order to conveniently release the latter from said clamp, the clamping bars must be first separated to relieve said tension. When this has been done, the curler rod with the strand wound thereon is free to be shifted slightly in a longitudinal direction relative to the clamp so as to disengage the ratchet on the rod from the pawl of the clamp, whereupon the unwinding of the strand from the rod by rotation of the latter may be accomplished. While performing this operation, the operator must hold the clamp while the rod is being shifted. In contradistinction, the present device provides a more simple and efficient manner of releasing the curler rod for the purpose of unwinding the strand therefrom, inasmuch as it is only necessary for the operator to press upon the spring arm 30 to disengage the pawl 34 and ratchet whereupon the strand may be unwound from the rod by a direct movement of the latter away from the clamp.

It will be noted in the construction shown it will not be possible for the operator to bend the pawl finger-piece 35 so as to unduly strain it, since when the pawl finger-piece 35 is moved sufficiently to release the pawl 34 from the ratchet 29, such pawl finger-piece 35 will abut against the finger-piece 36. This feature is particularly important inasmuch as the resilient element 33 is relatively delicate and may be easily injured by excessive strain. It has been found that the squeezing movement necessary to release the pawl 34 by moving the pawl finger-piece 35 against the abutment 36 is most satisfactory, and is more susceptible to ready actuation by the operator.

When the finger-piece 35 is moved into contact with the abutment 36 which limits its movement, the pawl will be lifted out of the ratchet 29 which will then be free. It is to be understood, however, that the present invention also includes other relationships between the pawl finger-piece 35 and the abut-

ment finger-piece 36 which will enable the operator to place her thumb against one finger-piece and the index finger against the other and readily release the combination, as previously described. It is also generally desirable to have both the abutment finger-piece and the pawl finger-piece located adjacent to one of the bearing elements or members 19 attached to the end of the bearing 14 of the 10 clamping member.

The electric heater 12 is shown as comprising a pair of elongated heating elements 37 which are curved transversely and adapted to engage on opposite sides of the wound strand of hair on the curler rod, as best shown in Figure 3. These heating elements are supported by upwardly converging plates 38 and to the intermediate portion of each plate is secured a handle 39 made of 20 suitable insulation material and through which electrical conductors 40 extend for conveying current to resistance coils disposed within each of the heating elements 37. On opposite sides of each handle the associated supporting plate 38 is provided with the extensions 41 which diverge outwardly relative to the extensions on the opposed plate. Each pair of the opposed extensions of the respective plates is provided with openings 30 42 to receive a spherical member 43. These members on opposite sides of the handles 39 constitute bearings about which the handles have a pivotal movement so that the heating elements 37 may be adjusted toward and 35 away from each other.

To assemble the opposed heating elements, their supporting plates and handles into an operative unit and provide means for forcing the heating elements toward each other so that 40 they will securely grip opposite sides of the hair strand, a contractile sleeve-like spring 44 is associated with each pair of extensions 41. Each spring is split longitudinally so as to receive said extensions therebetween 45 and thus exert a pressure upon the outer surfaces thereof which will normally force the heating elements toward each other. In order to prevent accidental displacement of the spring members 44, each of them is cut away 50 along one of its longitudinal edges, as indicated at 45, to provide at the ends of the sleeve a pair of lugs 46. The length of the cut out portion 45 is substantially equal to the width of the adjacent extension 41 so 55 that the latter will engage in said cut out with the lugs 46 overlapping the edges of the extension and thus preventing a lateral shifting of the spring member relative to the adjacent handles 39.

From the foregoing, it will be apparent that by compressing the free ends of the handles 39 the heating elements 37 may be spread apart against the action of the springs 44, preparatory to mounting the heater in operative relation to a hair strand, and that upon

release of said handles said spring members will be effective to clamp the heating elements against the strand and thus maintain the heater in position for application of heat to the hair being waved. 70

What is claimed is:

1. In combination, a protector or clamp for gripping a hair strand, a curler rod upon which said hair strand is wound, a pawl and ratchet mechanism operating between said clamp and curler rod for holding the latter against backward rotation when the hair strand is wound thereon, and a finger abutment carried by said clamp in such proximity to said pawl that the operator may 75 engage each with a finger and release the pawl from the ratchet by exerting pressure with the fingers on said finger engaged parts. 80

2. In combination, a protector or clamp for gripping a hair strand, a curler rod upon which said hair strand is wound, a pawl and ratchet mechanism operating between said clamp and curler rod for holding the latter against backward rotation when the hair strand is wound thereon, and a finger abutment carried by said clamp in such proximity to said pawl that the operator may engage each with a finger and release the pawl from the ratchet by exerting pressure with the fingers on said finger engaged parts, said 90 finger engaged parts being so arranged that a release will be effected by squeezing them together. 95

3. In combination, a clamp including bars for gripping a hair strand therebetween, a 100 curler rod supported for rotation upon said clamp and about which said hair strand is wound and tensioned by rotating the rod, interengaging means on said clamp and rod preventing rotation of the latter in one direction so as to maintain said strand under tension, and fixed and movable finger abutment 105 means adapted to be actuated by the thumb and index finger carried at the end of said clamp adjacent said interengaging means to 110 render inoperative said interengaging means whereby to release said tension without separating the bars of said clamp. 115

4. In combination, a clamp including bars pivotally connected at one end and movably 120 clamped at the other end for gripping a hair strand therebetween, a curler rod supported for rotation upon said clamp and about which said hair strand is wound and tensioned by 125 rotating the rod, means positioned on one of said bars adjacent said pivotal connection to hold said rod on said clamp and retain the same against rotation in one direction, and fixed and movable finger abutment means 130 adapted to be actuated by the thumb and index finger carried at the end of said clamp adjacent said interengaging means to release said holding means so that said strand may be unwound from said rod by a direct movement of the latter away from said clamp. 135

5. In combination, a clamp including bars pivotally connected at one end and movably clamped at the other end for gripping a hair strand therebetween, a curler rod supported for rotation upon said clamp and about which said hair strand is wound and tensioned by rotating the rod, a pawl and ratchet mechanism positioned on one of said bars adjacent said pivotal connection permitting rotation of said rod in one direction only and operable to maintain said strand under tension and to hold said rod on said clamp, and fixed and movable finger abutment means adapted to be actuated by the thumb and index finger carried at the end of said clamp adjacent said interengaging means to disengage the elements of said mechanism so that said strand may be unwound from said rod without releasing the strand from between the bars of said clamp. 70
15. In combination, a clamp including co-operating bars pivotally connected at one end and movably clamped at the other end for gripping a strand of hair therebetween, bearing members at the ends of one of said bars, a curler rod supported by said bearing members, a ratchet on said rod and a spring arm, positioned on one of said bars adjacent said pivotal connection having a pawl engageable with said ratchet, said arm further having a flat extension projecting beyond said pawl and parallel to the axis of said ratchet and constituting a fingerpiece adapted to be manipulated to disengage the pawl from said ratchet. 80
20. In combination, a clamp including co-operating bars pivotally connected at one end and movably clamped at the other end for gripping a strand of hair therebetween, bearing members at the ends of one of said bars, a curler rod supported by said bearing members, a ratchet on said rod and a spring arm carried by the last-named bar and having a pawl engageable with said ratchet, said arm further having an extension projecting beyond said pawl and constituting a fingerpiece adapted to be manipulated to disengage the pawl from said ratchet. 85
25. In combination, a clamp including co-operating bars for gripping a strand of hair therebetween, bearing members at the ends of one of said bars, a curler rod supported by said bearing members, a ratchet on said rod and a spring arm carried by the last-named bar and having a pawl engageable with said ratchet, said arm further having an extension projecting beyond said pawl and constituting a fingerpiece adapted to be manipulated to disengage the pawl from said ratchet, and a second fingerpiece on one of said bearing members disposed adjacent the first-named fingerpiece, said second-named fingerpiece serving as a finger abutment whereby the first-named fingerpiece may be conveniently manipulated and also serving to limit movement of said first-named fingerpiece. 90
30. In combination, a clamp including co-operating bars for gripping a strand of hair therebetween, bearing members at the ends of one of said bars, a curler rod supported by said bearing members, a ratchet at one end of said rod and disposed adjacent one of said bearing members, and a spring arm having one end secured to said clamping bar contiguous to one of said bearing members and provided adjacent its free end with a pawl engageable with said ratchet, the free extremity of said arm constituting a fingerpiece, and a second fingerpiece forming a part of the last-named bearing member and arranged adjacent the first-named fingerpiece, said second-named fingerpiece serving as a finger abutment whereby the first-named fingerpiece may be conveniently manipulated and also serving to limit movement of said first-named fingerpiece. 95
35. In combination, a clamp including co-operating bars for gripping a strand of hair therebetween, bearing members at the ends of one of said bars, a curler rod supported by said bearing members, a ratchet on said rod and a spring arm carried by the last-named bar and having a pawl engageable with said ratchet, said arm further having an extension projecting beyond said pawl and constituting a fingerpiece adapted to be manipulated to disengage the pawl from said ratchet, and a second fingerpiece disposed adjacent the first-named fingerpiece, said last-named fingerpiece being located on said last-named bar and serving as a finger abutment and as a stop means for said spring arm. 100
40. In combination, a protector or clamp including bars pivotally connected at one end and movably clamped at the other end for gripping a hair strand, a curler rod upon which said hair strand is wound, a pawl and ratchet mechanism intermediate between said clamp and said curler rod for holding the latter against backward rotation when the hair strand is wound thereon, and a finger engageable part or abutment engageable by one finger while the said pawl is engageable by another finger so that pressure exerted thereon by the fingers will release said pawl from the ratchet, said pawl and finger abutment being positioned on one of said bars adjacent said pivotal connection. 105
45. In combination, a protector or clamp including bars pivotally connected at one end and movably clamped at the other end for gripping a hair strand, a curler rod upon which said hair strand is wound, a pawl and ratchet mechanism intermediate between said clamp and said curler rod for holding the latter against backward rotation when the hair strand is wound thereon, and a finger engageable part or abutment in proximity to said pawl and engageable by one finger while the said pawl is engageable by another finger so that pressure exerted thereon by the fingers will release said pawl from the ratchet, said pawl and finger abutment being positioned on one of said bars adjacent said pivotal connection. 110
50. In combination, a clamp including co-operating bars for gripping a strand of hair therebetween, bearing members at the ends of one of said bars, a curler rod supported by said bearing members, a ratchet at one end of said rod and disposed adjacent one of said bearing members, and a spring arm having one end secured to said clamping bar contiguous to one of said bearing members and provided adjacent its free end with a pawl engageable with said ratchet, the free extremity of said arm constituting a fingerpiece, and a second fingerpiece forming a part of the last-named bearing member and arranged adjacent the first-named fingerpiece, said second-named fingerpiece serving as a finger abutment whereby the first-named fingerpiece may be conveniently manipulated and also serving to limit movement of said first-named fingerpiece. 115
55. In combination, a clamp including co-operating bars for gripping a strand of hair therebetween, bearing members at the ends of one of said bars, a curler rod supported by said bearing members, a ratchet at one end of said rod and disposed adjacent one of said bearing members, and a spring arm having one end secured to said clamping bar contiguous to one of said bearing members and provided adjacent its free end with a pawl engageable with said ratchet, the free extremity of said arm constituting a fingerpiece, and a second fingerpiece forming a part of the last-named bearing member and arranged adjacent the first-named fingerpiece, said second-named fingerpiece serving as a finger abutment whereby the first-named fingerpiece may be conveniently manipulated and also serving to limit movement of said first-named fingerpiece. 120
60. In combination, a clamp including co-operating bars for gripping a strand of hair therebetween, bearing members at the ends of one of said bars, a curler rod supported by said bearing members, a ratchet at one end of said rod and disposed adjacent one of said bearing members, and a spring arm having one end secured to said clamping bar contiguous to one of said bearing members and provided adjacent its free end with a pawl engageable with said ratchet, the free extremity of said arm constituting a fingerpiece, and a second fingerpiece forming a part of the last-named bearing member and arranged adjacent the first-named fingerpiece, said second-named fingerpiece serving as a finger abutment whereby the first-named fingerpiece may be conveniently manipulated and also serving to limit movement of said first-named fingerpiece. 125
